UNITED STATES PATENT OFFICE.

JOSEPH J. SPRENGER AND RASMUS L. SORENSEN, OF INDIANAPOLIS, INDIANA.

DESIGN FOR A DRAWER PULL OR THE LIKE.

Application filed May 21, 1928. Serial No. 26,797. Term of patent 7 years.

To all whom it may concern:

Be it known that we, JOSEPH J. SPRENGER and RASMUS L. SORENSEN, citizens of the United States and Denmark, respectively, residing both at Indianapolis, in the county of Marion and State of Indiana, have invented a new, original, and ornamental Design for Drawer Pull or the like, of which the following is a specification, reference being had to the accompanying drawing, forming a part thereof, in which—

Fig. 1 is a side elevation showing panel surfaces on the handle grip, which contain dice

face designs, and in which Fig. 2 is a sectional view taken in the proximity of line 2—2, Fig. 1, showing that the cross section of the grip portion corresponds in shape to dice.

We claim:

The ornamental design for a drawer pull or the like, as shown and described.

In testimony whereof, we have hereunto set our hands on this 15th day of May, 1928,
A. D.

JOSEPH J. SPRENGER.
RASMUS L. SORENSEN.
